SWITCHING MECHANISM.

1,105,349.

Specification of Letters Patent. Patented July 28, 1914.

Application filed June 24, 1912. Serial No. 705,413.

To all whom it may concern:

Be it known that I, CHARLES A. BALS, a citizen of the United States, residing at Chicago, in the county of Cook and State of Illinois, have invented a certain new and useful Improvement in Switching Mechanism, of which the following is a full, clear, concise, and exact description, reference being had to the accompanying drawings, forming a part of this specification.

My invention relates to intercommunicating telephone systems and particularly to switching apparatus that is of particular service in connection with such systems.

I will explain my invention more fully by reference to the accompanying drawings showing the preferred form of the invention as it is embodied in connection with one type of intercommunicating telephone systems and in which—

Figure 1 is a diagrammatic view of an intercommunicating system; Fig. 2 is a view in elevation, partially in section, of my improved switching mechanism; Fig. 3 is a view on line 3 3 of Fig. 2; Fig. 4 is a plan view of the structure shown in Fig. 3, partially in section; Fig. 5 is a view on line 5 5 of Fig. 3; Fig. 6 is a view on line 6 6 of Fig. 3.

Like parts are indicated by similar characters of reference throughout the different figures.

I will first describe the circuit arrangement illustrated in Fig. 1 and which shows three stations A, B, C, the apparatus at each of which including a telephone receiver 1, a telephone transmitter 2, a telephone switch hook 3 for including the telephone transmitter and receiver in circuit with and excluding from the circuit of telephonic conductors 4 and 5 which are extended into multiple connections with the contact springs 6 and 7 of keys 8 (individual to each of the lines extending to the stations where such keys are located) when the key 9 is in the position indicated at station B. Each of the keys 8 at each of the stations is provided with contacts 10 and 11 which are normally separated from the contacts 6 and 7 but which are, respectively, engaged thereby when the key 8 at a station which is calling any of the other stations of the intercommunicating system or any station which is called from an exchange is depressed, it being assumed that a line called from an

exchange is free for selection or that the called intercommunicating line is free for appropriation by the calling intercommunicating party.

When the telephonic equipment at an intercommunicating station is thus brought into telephonic connection with any telephone line extending to such station, such telephone equipment is held in this relationship (while the receiver is off its hook) by means of the dog 12 that engages a lug 13 provided upon the key 9, such engagement being illustrated at station B. Each dog 12 is pivotally mounted upon a swinging plate 14 which is engageable by a pin 15 provided upon the lower end of each bar 16. The bar 16 at each station is provided with pins 17 that are worked upon by the keys 8 when the keys are depressed. The equipment at station A is in condition to permit the keys 8 thereat to be depressed. When a key thus free to be depressed is so depressed, the free end of the plate 14 is engaged under the lug carried by the upper end of the armature 18 as illustrated at station B whereby the element of key 19 (which moves bodily with the plunger element 9 and is pivotally mounted thereupon) is removed from the path of travel of the plunger element of the key 9 whereby the lug 13 is free to ride under the dog 12 so that the nose of said dog will engage the lug, as illustrated at station B, to hold the key in its depressed position as is necessary in the establishment of telephonic connection between the associate telephone set 1, 2 and the line to which the actuated key 8 is individual.

The telephonic connection thus mechanically held is adapted to be broken by the associate magnet 20 which, when energized, swings the armature 18 to break the engagement between the armature and the associate plate 14 whereupon the dog 12 carried by such plate is raised out of engagement with the lug 13 to permit the plunger element of the key 9 automatically to be thrust back so as to break the previously held telephonic connection. To this end the magnet 20 at one or more of the stations (the equipment now to be described being shown at station A only) is provided with a controlling circuit and suitably associated switching mechanism, such circuit being traceable from the lower pole of the battery 52, the winding of magnet 20, the now engaged contacts 22, 23, 110

the contacts 24 and 25 of the holding key mechanism to the upper terminal of the battery 52. The contacts 24 and 25 are normally disconnected in order that the magnet 5 20 may remain inert during the time the associate telephone outfit 1, 2 is mechanically locked in circuit. These latter contacts form part of unitary switching mechanism that includes the contacts 26 and 27 that are normally separated to keep open the bridge conductor across the sides of the trunk line 29, 30 and which bridge conductor includes a magnet 28. When the magnet 28 is energized upon the closure of the contacts 26, 27 10 (which closure is effected when the closure of contacts 24 and 25 is effected with the results stated) contacts 31 and 32 are closed for the purpose of maintaining the continuity of the bridge conductor through the winding 28 when the holding key lever 33 is released. The armature of the magnet 28 15 may be provided with a visual signal attachment 34 to indicate to the operator whether or not the trunk line is held. The trunk line extends to an exchange (which need not be illustrated) the bridge which is established through the magnet 28 replacing the bridge that was previously established across the trunk line through the telephonically released equipment 1, 2. The magnet 28 is in 20 high resistance so that when the telephone equipment 1, 2 is again bridged across the trunk line the magnet will be shunted as a consequence of the comparatively low resistance of the bridge conductor including the 25 elements 1 and 2.

The purpose of the holding magnet 28 is to maintain the equipment that is associated with the trunk line at the exchange to which 40 the trunk line extends in *status quo* whether such trunk line extends to an exchange where it is either manually or automatically extended or not.

As the circuit arrangement is illustrated 45 in Fig. 1, station B has called station A and the latter station has responded. Station C has the key or button 17 connected to the line from station A depressed, the apparatus at station C being in condition to enable the 50 party thereat to test the A line. The operator at station B in order to signal station A depresses the key 9 to its innermost limit to bring the contacts 35 together whereby signaling circuit is established which may be 55 traced from the upper terminal of the signaling battery 36 through the signal receiver 37 at the called station, through the contacts 38, the lower contacts of the switch hook 3 when electrically connected by said 60 switch hook when supporting its associate telephone receiver 1, the conductor 39, the lower line side of the called line, the engaged contacts 7, 11 of the key 8 at the calling station which is then depressed, the contacts 35 65 at the calling station, to the lower side of the

battery 36. I have described the system illustrated in Fig. 1 with some degree of particularity in order that the mechanism which forms the subject matter of the present application may be more thoroughly understood. 70

Referring now more particularly to figures illustrating the mechanical construction of the switching mechanism, the armature 40 of the electro-magnet 20 has a fixed pivot 75 41, this fixed pivot being provided upon the upper end of the plate 42. The key 43 that controls the ringing, testing, and talking circuits is mounted upon the upper end of a vertically movable plate 9 that constitutes a 80 plunger, this plunger carrying the wedging devices 45 for working the circuit controlling springs 23, 46 that are to be controlled thereby. A dog 19 (Fig. 5) is pivotally mounted upon the plunger 9 which is pressed 85 upon by a spring 48, this spring 48 (when free so to do) pressing the lower end of the dog 19 into the stationary slot 49 for the purpose of preventing the plunger 9 from being depressed. When the plunger has been 90 depressed and is free to be elevated a restoring spring 50 serves to effect the elevation. Normally the element 19 is in engagement with the slot 49. If the line wanted 95 is busy, then the plunger can only be slightly depressed to a testing position (station C, Fig. 1), as the magnet 20 will be energized. In the testing operation the key 8 at the testing station is fully depressed, fully to 100 depress the corresponding bar 16, whereby the bar is brought into the path of the armature 40, the bar 16, through the intermedia- 105 tion of the pin 15, bringing the upper end of the plate 14 into line with the recess 51 in the armature 40. If the tested line is 110 busy the magnet 20 at the testing station will be energized to withdraw the portion 18 of the armature 40 out of engagement with the upper end of the plate 14 so that the spring 48 will be free to move the dog 19 into en- 115 gagement with the slot 49 after the actuated button 8 at the testing station is released, the reengagement of the dog 47 being effected before the plunger 9 is depressed, this de- 120 pression being effected after the key 8 at the testing station has been released. If the plunger 9 is arrested by the portion of the dog 19 that enters the slot 49, then the testing party will know that the tested line is 125 busy. The circuit that is established for the magnet 20 when it is thus connected with the tested busy line may be traced from the lower pole of the battery 52 through the winding of magnet 20 at the testing station, the testing contacts 53 that are engaged 130 when a button 8 at the testing station is fully depressed, the contacts 54, the contacts 7 and 11 of the fully depressed button 8 at the testing station, the upper portion of the conductor 39 at the station being tested, a con-

tact 55 and a contact 46 engaging the same, the switch hook 3 at the station of the busy line, the telephone receiver and transmitter at such station, one of the contacts 46 and 5 engaging contact 56 at the busy station, assuming that the button 9 at the busy station is not depressed and that the receiver at the busy station is merely removed from its switch hook. Thence by the conductor 57, 10 impedance 58, to the upper pole of the battery 52. The test circuit that is present in connection with a busy station which previously sought and obtained connection with another line is apparent when it is explained 15 that the line of the tested station is bridged by the contacts 60 at the tested station when test button 9 at the tested station is depressed. If the tested line is idle, the magnet 20 at the testing station will not be energized and 20 the armature 40 will therefore have its portion 18 in position to retain engagement with the upper end of the plate 14, the plate 14 then engaging the upper end of the dog 19 to move the upper end of the dog inwardly 25 against the force of the spring 48 whereby the lower end of the dog is maintained out of the slot 49, in which condition of the apparatus the plunger 9 may be fully depressed to the ringing position and may remain in 30 its nearly depressed position for establishing a talking circuit with the wanted station. The plunger 9 is provided with a projection 59 having a T-head which overlies the plane of movement of the bar 16 when the plunger 35 9 is not depressed so that the bar 16 may be moved beneath such T-head.

When a button 8 is fully depressed (and its depression occurs before the plunger 9 is to be depressed) the bar 16 moved by the 40 button 8 underlies the T-head of the projection 59 so that the plunger 9 cannot be depressed while a button 8 is fully depressed (see station C). Thus the button 43 of the plunger 9 cannot be depressed even though 45 the dog 19 is out of engagement with the slot 49 (which is the case when the bar 16 is depressed by a button 8, owing to the movement of the plate 14 by the pin 15) whereby the seeking party is prevented 50 from operating the plunger 9 to connect his telephone with a busy line. The projection 59 is brought into line with the bar 16 when the plunger 9 is depressed to a talking position so that the bar 16 cannot be moved from 55 its normal position by a key 8 for the purpose of bringing the telephone at the seeking station into connection, it being necessary for the telephone receiver at a seeking station to be restored upon its switch hook 60 before telephone connection may be established between such seeking station and a second sought line. The plunger 9, when depressed to a talking position, is maintained in such depressed condition by the 65 dog 12 which is pressed by a spring 121

into engagement with the projection 13 (see station B and Fig. 6). When the conversation is finished, circuit is established through the magnet 20 which attracts its armature 40 to disengage the armature portion 18 from the upper end of the plate 14 whereupon the spring 50 restores the plunger. 70

The circuit that is established through the magnet 20 when conversation is through 75 may be traced from the lower pole of the battery 52 through the winding of the magnet, the engaging contacts 22 and 23 (see station B) the lower contacts of the switch hook 3 at the same station with the magnet 80 20 then engaged by the switch hook to which the telephone receiver has been returned, the then engaged contact 60 to the under side of the corresponding (or home) side, the impedance 58 of such line to the 85 upper terminal of the battery 52.

The plate 42 which supports the magnet 20, the plate 14, the armature 40; the plunger 9, the dog 12, and other parts as will be understood is removably secured to the 90 framework 61 that carries the bar 16, the key mechanism 8 and the associate springs, the stems of screws 62 being received within upwardly opening slots in the frame 61, and a groove in a post 63 receiving an up- 95 right portion of the frame 61 as indicated in Fig. 5. The opening 64 in the frame 61 is sufficiently large to permit the head of key 43 to be drawn downwardly therethrough after the magnet structure and its 100 associate parts have been moved upwardly and outwardly.

The intercommunicating telephone system herein shown forms the subject matter of my co-pending application Serial No. 105 705,412, filed June 24, 1912.

While I have herein shown and particularly described the preferred embodiment of my invention I do not wish to be limited to the precise details of construction or circuit 110 arrangement shown as changes may readily be made without departing from the spirit of the invention, but

Having thus described my invention I claim as new and desire to secure by Letters 115 Patent the following:

1. Switching mechanism including a switch actuated bar; a swingingly mounted element 14 adapted to be operated by said bar; an electro-magnet having an armature 120 serving, when unattracted, to hold the element 14 against movement, the bar serving to bring said element 14 into engagement with the armature; a switch; and means whereby said element 14 holds the switch in 125 an actuated position when said element 14 is held by the armature.

2. Switching mechanism including a switch actuated bar; a swingingly mounted element 14 adapted to be operated by said 130

- bar; an electro-magnet having an armature serving, when unattracted, to hold the element 14 against movement, the bar serving to bring the element 14 into engagement with the armature; a switch; and a dog whereby the element 14 holds the switch in an actuated position when said element 14 is held by the armature.
3. Switching mechanism including a switch actuated bar; a swingingly mounted element 14 adapted to be operated by said bar; an electro-magnet having an armature serving to hold the element 14 against movement, the bar serving to bring said element 14 into engagement with the armature; a switch; and means whereby said element 14 holds the switch in an actuated position when said element 14 is held by the armature.
- 20 4. Switching mechanism including a switch actuated bar; a swingingly mounted element 14 adapted to be operated by said bar; an electro-magnet having an armature serving to hold the element 14 against movement, the bar serving to bring the element 14 into engagement with the armature; a switch; and a dog whereby the element 14 holds the switch in an actuated position when said element 14 is held by the armature.
- 25 5. Switching mechanism including a switch actuated bar; a swingingly mounted element 14 adapted to be operated by said bar; an electro-magnet having an armature serving, when unattracted, to hold the element 14 against movement, the bar serving to bring said element 14 into engagement with the armature; a switch; and a dog for engaging the switch to prevent its movement and released from engagement with the switch by said element 14 when held by the armature.
- 30 6. Switching mechanism including a switch actuated bar; a swingingly mounted element 14 adapted to be operated by said bar; an electro-magnet having an armature serving to hold the element 14 against movement, the bar serving to bring said element 14 into engagement with the armature; a switch; and a dog for engaging the switch to prevent its movement and released from engagement with the switch by said element 14 when held by the armature.
- 35 7. Switching mechanism including a switch actuated bar; a swingingly mounted element 14 adapted to be operated by said bar; an electro-magnet having an armature serving to hold the element 14 against movement; the bar serving to bring said element 14 into engagement with the armature; a switch; and a dog normally engaging the switch to prevent its movement and disengaged from the switch by said element 14 when said element 14 is engaged by the armature.
- 40 8. Switching mechanism including a switch actuated bar; a swingingly mounted element 14 adapted to be operated by said bar; an electro-magnet having an armature serving to hold the element 14 against movement; the bar serving to bring said element 14 into engagement with the armature; a switch; and a dog normally engaging the switch to prevent its movement and disengaged from the switch by said element 14 when said element 14 is engaged by the armature.

In witness whereof, I hereunto subscribe my name this twentieth day of May A. D., 1912.

CHARLES A. BALS.
